[57] CLAIM

The ornamental design for cup with lid, as shown and described.

DESCRIPTION

FIG. 1 is a perspective view of a cup with lid showing our new design;

FIG. 2 is a front elevational view thereof, the opposite side being a mirror image;

FIG. 3 is a top plan view thereof;

FIG. 4 is a bottom plan view thereof;

FIG. 5 is a left side elevational view thereof;

FIG. 6 is a right side elevational view thereof;

FIG. 7 is a cross-sectional view taken along line 7—7 of FIG. 6;

FIG. 8 is a top plan view thereof, the spout in an open position; and,

FIG. 9 is a cross-sectional taken along line 9—9 of FIG. 8.

FIG. 1

FIG. 2

FIG.3

FIG.4

FIG.5

FIG.6

FIG. 8

FIG. 7

FIG. 9

UNITED STATES PATENT AND TRADEMARK OFFICE
Certificate

Patent No. D. 362,156

Patented: September 12, 1995

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Toru Goto, Tokyo, Japan; Yukari Kawamu, Tokyo, Japan; and Shelley Nehrt, Barrington, Illinois.

Signed and Sealed this Eleventh Day of May 2004.

ALAN P. DOUGLAS
